RHEOSTAT

Filed June 21, 1930

UNITED STATES PATENT OFFICE

FREDERIC H. BULLINGER, OF BRONXVILLE, NEW YORK, ASSIGNOR TO WARD LEONARD
ELECTRIC COMPANY, A CORPORATION OF NEW YORK

RHEOSTAT

Application filed June 21, 1930. Serial No. 462,754.

This invention relates to an improved form of construction of rheostats and to the method of making rheostats.

The invention particularly relates to that 5 form of rheostat in which a movable contact arm passes over and makes successive engagement with a series of contacts to which a resistive conductor is connected.

One object of the present invention is to 10 provide an improved contact between the resistive conductor and the fixed contacts of the rheostat which will insure good electrical connection between the parts, and also be permanent and unaffected in the course of manufacture when subjected to the insulating and 15 enameling process such as occurs during the manufacture of the usual enameled plate rheostats. Another object is to permit the convenient use of fixed contacts of rectangular 20 shape, as distinguished from the usual round form of contact buttons, the rectangular form being preferable, particularly for heavy-duty rheostats, where a comparatively large contact surface is necessary and where economy 25 in space is desirable. Another object is to provide means for insuring proper position of the fixed contacts of the rheostat and the maintaining of such position and of the resistive conductors during the insulating and 30 enameling process. Heretofore, it has been a matter of considerable difficulty and expense in properly positioning the fixed contacts and resistive conductor in this type of rheostat, not only during the preparation of 35 the same for the firing, but also during the vitrifying of the enamel material in the baking, or firing, operation. Even though great care be taken in properly positioning the parts before firing and in introduction to the firing 40 furnace, the heating often causes the parts to shift their relative positions, due to the annealing and relief of strains, so that when the enameled plate is withdrawn from the furnace, it is not infrequently found that the 45 contacts and resistive conductor have shifted

their positions sufficiently to cause electrical connection between adjoining sections, giving short-circuit connections and necessitating, in some instances, the loss and discarding of the device. By the present invention, the parts 50 are not only securely maintained in fixed position before the firing operation, but their fixed relative position is insured by auxiliary means provided for that purpose during the firing operation. Other objects include a reduction 55 in cost of manufacture, the securing of uniformity in production, the avoiding of rejections and the production of a permanently dependable and durable product.

The invention will be understood by reference to the following description and accompanying drawing in which: Fig. 1 is a front view of one form of rheostat embodying the invention, part of the insulating material being indicated as broken away to reveal the resistive conductors in their relation to the fixed contacts; Fig. 2 is a front view of one form of improved contacts before connection to the resistive conductor and before assembling; Fig. 3 is a side view thereof; Fig. 4 is a back 60 view thereof; Fig. 5 is a perspective view showing one form of resistive conductor prepared for union with the fixed contacts and also showing two of the fixed contacts secured thereto; Fig. 6 is a plan view of the contacts 65 and resistive conductor and showing the temporary securing means, ready for placing upon the supporting plate of the rheostat before application of the insulating material.

Referring to Fig. 1, the usual metal plate 80 is indicated having an out-turned edge 1 provided with the usual insulating ground coat 2. The fixed contacts 3 are shown of rectangular form and are passed over by a conductor 4 indicated by dotted lines and carried by the rotatable arm 5 of the rheostat. The terminals 6 are indicated as being connected to opposite fixed contacts, so that when the arm is rotated, more or less of the resistive conductors 7 will be included in the cir- 85 90

cuit. The resistive conductors and base of the fixed contacts are covered by and held securely in position by a coating of insulating material 8, which is preferably an adhesive vitreous enamel coating. Although Fig. 1 indicates one form of rheostat as an example of the application of this invention thereto, it may be made in any suitable form for the particular purpose desired.

My improved form of contact shown in Figs. 2, 3 and 4, is of general rectangular form and has projecting portions 3a at the ends of its base which are adapted to be covered by the insulating coating 8, so as to assist in securely and firmly holding the fixed contacts in position on the supporting plate after completion of the rheostat. In the bottom of the contact is a slot 3b extending lengthwise thereof and extending well into the body of the contact. The sides of the contact are bulged outwardly as shown at 3c, in the region of the slot. The contact is provided, in the particular form shown, with a pair of projecting lips 3d at the front surface thereof near the center and extending cross-wise to the face of the contact.

Referring to Fig. 5, the resistive conductor 7 is shown looped back-and-forth upon itself in order to give the required resistance between contacts, and at its outer portion is bent to return for connection with the next contact from which it passes inwardly and is again bent to return for connection with the succeeding contact. In some cases, the resistive conductor may be located on one side only of the contacts, in which case the conductor is bent at the contact to extend outwardly from the same portion at which it joined the contact. At the portions of the resistive conductor where it is to be connected to the contacts, the conductor is looped outwardly as shown at 9 in Fig. 5, for the purpose of providing means for connection to the fixed contacts. According to the method of assembly, the resistive conductor is looped as already described and then the contacts 3 are successively added to the loops 9 of the resistive conductor by causing these loops to project within the slots 3b. The sides 3c of the contacts are then firmly compressed toward the loop portions 9 of the resistive conductor, so as to cause the metal of the contacts to firmly grip, surround and embed the loops 9, so that when the contacts are thus united with the resistive conductor, the bulging sides 3c of the contacts are forced inwardly to such an extent around the loops 9 that the sides of the contacts have inwardly depressed portions as indicated at 3e, instead of outwardly bulging portions. This compression may, of course, be conveniently accomplished by an automatic compressor, which will cause the union of the contacts with the resistive conductor in rapid succession.

When all of the required number of fixed

contacts are united with the resistive conductor to form the complete set necessary for the rheostat, the parts are then assembled in their final position by means as shown in Fig. 6. Here a circular element 10, in this instance an iron or steel wire, is provided for securely holding the contacts in place. The contacts are united with the element 10 and positioned in circular form under the same by means of the lips 3d of the contacts embracing the circular element. The contacts are positioned in proper relation to each other on the circular element 10 and then pressure is applied to the lips 3d, so as to cause them to firmly grip the wire 10, as by forcing the lips toward each other, or by compression against the wire. When the contacts are thus held in their final and relative positions, the resistive conductor may be then properly bent and spaced and are then retained in their final position by the fixed position of the contacts.

The assembled set, together with the retaining element 10, is then placed upon its supporting plate in its final position thereon, and the enamel material, or other insulating coating is then applied over the resistive conductor and around the base of the fixed contacts, after which the parts are placed in the firing furnace to mature the enamel. In some cases, the insulating material may be placed in an oven, or otherwise baked or dried, to form the insulating protective coating, but a vitreous enamel coating is far preferable to other materials, owing to its high insulating qualities, imperviousness to moisture, and durability.

After removal from the furnace, the retaining element 10 is removed from the fixed contacts, as by pulling it outwardly from the face of the contacts, or by cutting it out; and then the lips 3d and surfaces of the fixed contacts are ground down, or milled, so as to lie in the same plane and present smooth and even surfaces for engagement with the movable contact, or contacts of the rheostat arm. The movable contact arm is then secured to the rheostat plate in any of the usual known ways, which completes the assembly of the rheostat.

It is evident that this invention permits the convenient use of rectangular contacts, and it has been demonstrated that my improved form of connection between the resistive conductor and the fixed contacts gives an excellent electrical connection, which is uniformly dependable and permanent. This form of electrical contact is perfectly maintained, even during and after the firing in forming the enamel coating. Also, the form of the contact is such that it may be readily and conveniently cast in the form shown, and may even be stamped out from sheet metal and the slot in its under side formed by a punching machine. Instead of forming a hole in the bottom of the fixed contact, the bottom of the

contact may be slotted by cutting a groove across it, or lengthwise of it, and having the projection or loop in the resistive conductor, or a portion of the conductor, extend into this slot and then the two sides pressed together, or folded over the resistive conductor, so as to partially, or wholly, embed the same to form a permanent electrical contact.

Instead of using a ring or wire 10 secured to the faces of the contacts by projecting lips as described, for positioning them, the circular element might be otherwise secured, as by use of a ring brazed to the surface of the contacts. In some cases, I have soldered the circular element to the contacts, and although the solder may melt during the enameling process, yet distortion of the parts is prevented before melting of the solder, so that satisfactory results have been obtained by this means. The retaining means has also been accomplished by first forming an integral ring of brass, or other material, and forming the contacts by slotting the ring on the rear side, so as to form a series of fixed contacts held together and retained in proper position by the portion of the uncut material which is left at the face of the contacts in the form of a continuous ring. This, of course, is turned or ground off after the firing of the enamel.

Although I have described a preferred embodiment of this invention, it is evident that various modifications may be made and the method modified, without departing from the scope thereof; and where I have referred in the claims to maturing the insulating coating, it is to be understood that this applies to any form of insulating coating and to the drying, setting, baking, firing, or the like, of the coating.

I claim:

1. A rheostat comprising an insulating support, a resistive conductor on said support, fixed contacts on said support, said contacts having openings on their inner ends and extending lengthwise towards the faces thereof receiving and compressing portions of said conductor, and an insulating coating covering said conductor and embedding the inner ends of said contacts.

2. A rheostat comprising an insulating support, a resistive conductor, said conductor having outwardly projecting portions, fixed contacts on said support, said contacts being of rectangular form and having openings on their inner ends extending lengthwise and towards the faces thereof receiving and compressing said projecting portions, and an insulating coating covering said conductor and embedding the inner ends of said contacts.

3. A rheostat comprising an insulating support, a resistive conductor, said conductor having outwardly projecting looped portions, fixed contacts on said support, said

contacts being of rectangular form and having openings on their inner ends extending lengthwise and towards the faces thereof receiving said looped portions and the walls of said openings being compressed inwardly 70 and compressing said looped portions, and an insulating coating covering said conductor and embedding the inner ends of said contacts.

4. The method of making a rheostat which comprises forming openings in the inner ends of the contacts and extending lengthwise towards the faces thereof, forming the resistive conductor to have portions entering said openings, and compressing the sides of said contacts to cause the walls of said openings to engage said portions. 75

5. The method of making a rheostat which comprises forming openings in the inner ends of the contacts and extending lengthwise towards the faces thereof, forming the resistive conductor to have outwardly projecting portions entering said openings, and compressing the sides of said contacts to cause opposite sides of said openings to engage said portions. 80

6. The method of making a rheostat which comprises forming the contacts of rectangular shape and with openings at their inner ends extending lengthwise and towards the faces thereof, forming the resistive conductor to have outwardly projecting portions entering said openings, and compressing the side walls of said contacts to clamp said portions between them. 85

7. The method of making a rheostat having a series of contacts connected to a resistive conductor which comprises uniting with the outer portions of said contacts a positioning element, applying the contacts 90 and conductor to their support, applying an insulating coating over the resistive conductor and around the bases of the contacts, maturing said coating, and then removing said positioning element. 105

8. The method of making a rheostat having a series of contacts connected to a resistive conductor which comprises forming a series of openings in the outer portions of said contacts, placing a positioning element in said openings, applying the contacts and conductor to their support, applying an insulating coating over the resistive conductor and around the bases of the contacts, maturing said coating, and then removing said positioning element. 110

9. The method of making a rheostat having a series of contacts connected to a resistive conductor which comprises forming said contacts with projecting portions at the outer portions thereof, causing said projecting portions to engage a positioning element, applying the contacts and conductor to their support, applying an insulating coating over the resistive conductor and around the bases of 115

the contacts, maturing said coating, and then removing said positioning element.

10. The method of making a rheostat having a series of contacts connected to a resistive conductor which comprises mechanically connecting the outer portions of said contacts for positioning the same in their proper relative positions, applying the contacts and conductor to their support, applying an insulating coating over the resistive conductor and around the bases of the contacts, maturing said coating, and then removing the mechanical connection from the outer portions of said contacts.
